UNITED STATES PATENT OFFICE.

WILLIAM DUGUAY, OF LOWELL, MASSACHUSETTS.

PADLOCK.

Application filed April 16, 1923. Serial No. 632,248.

To all whom it may concern:

Be it known that I, WILLIAM DUGUAY, a citizen of Canada, residing at Lowell, in the county of Middlesex and State of Massachusetts, have invented certain new and useful Improvements in Padlocks, of which the following is a specification.

This invention relates generally to locks, having more particular reference to a combination operated padlock having a series of rotary elements which are set in proper relative arrangement to release the shackle.

The invention has for a general object to provide a novel and simple type of padlock presenting increased difficulty in being picked.

For further comprehension of the invention, and of the objects and advantages thereof, reference will be had to the following description and accompanying drawing, and to the appended claims in which the various novel features of the invention are more particularly set forth.

Fig. 1 of the drawings is a side view of a padlock constructed according to my invention.

Fig. 2 is a longitudinal sectional view thereof.

Fig. 3 is a transverse sectional view taken on the line 3—3 of Fig. 2.

Fig. 4 is an end view with part of the shackle broken away.

As here embodied my improved padlock comprises a pair of circular end plates 10 and 11 between which are a number of rings 12 laid face to face to be rotatable on a common axis, the axial element being in the form of a rod 13 extending from end to end through the padlock and having a head on each end. The shackle is indicated generally at 15 and is here shown as having a short leg 15^a and a long leg 15', suitable openings 16 and 17 being provided in the end plate 10 to receive these legs.

The leg 15' is formed with a number of longitudinally spaced projections 20 adapted to be engaged by locking disks enclosed within the rings 12, these disks being rotatable around the rod 13. I have here shown three of these disks which are numbered respectively 21, 22 and 23 and which are provided each with a notch 24 in the side thereof which is brought into registry with the shackle leg 15' to free the latter.

For properly setting these disks to releasing position the top disk 21, considering the

parts as shown in the drawing, is formed with an upwardly projecting hub element 26 which extends through a complementary opening in the top plate 10 and is formed with an enlarged head 27 for purposes of rotation. The middle disk 22 has an integral trunnion projection 28 which extends freely upward through the hub element 26 and is likewise formed with a head 29 for rotation purposes. The lower disk 23 is formed with a trunnion projection 30 which extends downward through a complementary opening in the bottom plate 11, and has also a head 31 on its lower end for purposes of rotation.

Each of the rings 12 is formed on its inner wall with a notch 33 of sufficient depth radially to allow of the shackle leg 15' moving laterally a slight distance, to free a lug 34 on the end of the leg 15^a from a shoulder on an undercut recess 35 on the plate 10. The openings in the plate 10 through which the legs of the shackle extend are elongated sufficiently to allow of the lateral movement of the shackle, the exterior portion of the shackle being formed as shown to cover these openings when the lock is closed.

Suitable numbers are placed around the perimeters of the plates 10, 11 and rings 12, while other numbers are placed on the exposed faces of the plates 10, 11 adjacent the heads 27, 29 and 31. These numbers are for setting purposes, as will be understood, although the numbers on the perimeters of the plates are merely dummy numbers to confuse anyone attempting to pick the lock. The rings 12 are of sufficient interior diameter to permit of their free rotation with the shackle in place and are held against lateral displacement by interlocking circumferential flange and recess formations 36 engaging them with one another and with the plates 10, 11.

To release the shackle the heads 27, 29 and 31 are turned to set the notches 24 in the disks 21, 22 and 23 in registry with the shackle leg 15', and the rings 12 are also turned to set the notches 33 therein in registry with this shackle leg. The shackle is then moved laterally to free the lug 34 on the leg 15^a from the recess 35, the parts being so proportioned that this movement is not sufficient to free the projections 20 on shackle leg 15' from the said disks in case the latter have not been properly set. The shackle is then pulled outwardly as usual.

Having thus described my invention what I claim as new and desire to protect by Letters Patent of the United States is as follows:

- 5 1. In a padlock, a shackle, a body comprising a pair of end plates, rotary rings located between said end plates, and disks enclosed within the body adapted to engage and lock the shackle, said disks being
- 10 formed with elements projecting through the said end plates for purposes of rotation, a part on said shackle adapted to be released from the body by lateral movement of the shackle, said rings normally holding
- 15 the shackle against lateral movement, and being each formed with a notch adapted to be brought into registry with the shackle to free the latter said notches being of a depth insufficient to permit of disengagement of
- 20 the shackle from the said disks by the said lateral movement of the shackle.
- 25 2. In a padlock, a body comprising end plates, rotary rings located between said end plates, a shackle having a short leg and a long leg, rotary locking disks enclosed with-

in the said body and having parts projecting from the ends thereof for turning purposes, a series of projections on the long leg of the shackle adapted to engage over the edges of the said disks to hold the shackle 30 against longitudinal movement, a projection on the short leg of the shackle adapted to engage in an undercut recess in one of the end plates, said rotary rings being adapted to prevent lateral movement of the shackle to free the projection on its short leg from the said recess, and being each 35 formed with a notch adapted to be brought into registry with the long leg of the shackle to permit of the said lateral movement said notches being of a depth less than the distance which said projections on the shackle engage over the said disks to prevent disengagement of the said projections from the 40 said disks by the said lateral movement of 45 the shackle.

In testimony whereof I have affixed my signature.

WILLIAM DUGUAY.
